[57] **CLAIM**

The ornamental design for an editing machine for graphic image and sound, as shown and described.

DESCRIPTION

FIG. 1 is a perspective view of an editing machine for graphic image and sound showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof;

FIG. 8 is a perspective view of another embodiment of editing machine for graphic image and sound showing my new design;

FIG. 9 is a top side elevational view of the embodiment of FIG. 8;

FIG. 10 is a left side elevational view of the embodiment of FIG. 8;

FIG. 11 is a front elevational view of the embodiment of FIG. 8;

FIG. 12 is a bottom plan view of the embodiment of FIG. 8;

FIG. 13 is a right side elevational view of the embodiment of FIG. 8; and,

FIG. 14 is a rear elevational view of the embodiment of FIG. 8.
